COMBINED SCARF AND BELT HANGER

Lenore T. Allen, 3316 Oakland,
Kansas City, Mo. 64129

Filed Mar. 17, 1976, Ser. No. 667,510

Term of patent 14 years

Int. Cl. D6—08

U.S. Cl. D6—251

FIG. 1 is a perspective view of a combined scarf and belt hanger showing my new design, the scarf and belt being shown in broken lines for illustrative purposes only;

FIG. 2 is a front elevational view, the rear being a mirror image thereof;

FIG. 3 is a side elevational view taken from the left of FIG. 1;

FIG. 4 is a side elevational view taken from the right of FIG. 1; and

FIG. 5 is a sectional view taken on line 5—5 of FIG. 2.

I claim:

The ornamental design of a combined scarf and belt hanger, as shown and described.
